UNITED STATES PATENT OFFICE

FREDERICK W. MONROE, OF ATLANTIC CITY, NEW JERSEY, ASSIGNOR TO MACKINTOSH HUTCHINSON, OF PHILADELPHIA, PENNSYLVANIA

MORTISING MACHINE

Application filed March 18, 1930. Serial No. 436,774.

My invention relates to wood working machines, more particularly to mortising machines, embodying a boring bit and a chisel. It has among its objects to simplify and cheapen the construction and number of parts without detracting from efficiency, thus making possible to replace the more expensive machines with the improved machine which will give practically as good if not better results and at a great reduction in the cost of construction, due to the novel features of construction embodied in the new machine. To the accomplishment of the foregoing and such other objects as may hereinafter appear the invention consists in the features illustrated in the selected embodiment of the invention, and sought to be clearly defined by the appended claims, reference being had to the accompanying drawings forming a part hereof and in which:

Figure 1 is a side elevation, partially in longitudinal section, illustrating one embodiment of the invention;

Figure 2 a plan view of Figure 1;

Figure 3 a cross section through the work-table elements on line 3—3 of Figure 1;

Figure 4 a vertical section through the upper end of the machine standard, showing the sheave for the cable by which longitudinal movement is given to the boring-bit and chisel;

Figure 5 a cross section on the line 5—5 of Figure 1;

Figure 6 a cross section on line 6—6 of Figure 1;

Figure 7, a modification in which the boring-bit and chisel operate in a vertical plane;

Figure 8, a modification showing an electric motor instead of a line-shaft driven pulley for rotating the boring-bit, the parts operating in a vertical plane;

Figure 9, a vertical elevation, similar to Figure 8, showing a hand lever for longitudinal movement of the boring-bit and chisel instead of a cable as in Figure 8;

Figure 10, a detail showing modified means for holding the line driven pulley from longitudinal movement on its shaft or spindle.

In the drawings, in the form illustrated in Figure 1, the numeral 1 indicates a suit-

able base or standard, which may be of hollow or other formation, and upon the upper end of which rests a platform plate 2, which may be secured thereto by any desired number of bolts 3. The platform or plate 2 supports the following elements when disposed for the boring-bit and chisel to operate in a horizontal plane as illustrated in Figure 1. The numeral 4 indicates a casting formed with a hollow base 5 and a tubular member 6 which serves as a boxing to receive a slideable tubular spindle 7 containing at one end a chuck 8 to receive the shank of a tubular chisel 9, the chuck and chisel being held in place by a set screw 10 passing through the end of the tubular spindle 7 and the chuck with its end bearing against the shank of the chisel so that the chuck and chisel will move with the tubular spindle in reciprocation of the spindle. The exterior of the chisel shank may be formed with a flange or collar 11 to bear against the end of the chuck and limit the insertion of the chisel therein, and the tubular spindle at its forward end may be formed with an external shoulder or flange 12 which will contact with the end of the tubular boxing 6 to limit the rearward reciprocation of the tubular spindle 7. The base of the casting 4 may be made with a flange 13 through which the bolts 3 may pass to secure the casting to the base plate 2. Within the tubular spindle 7 is a rotatable spindle or shaft 14 having, together with bushing 37 substantially the diameter of the interior of spindle 7 and having at its rear a reduced end 15 constituting an extension of the spindle 14, passing through a cap 16, secured by bolts 17, or otherwise to the end of spindle 7, and journaled in a boxing 18 and carrying a driving member which may be a pulley or sheave 19 driven by a line-drive belt 20, splined to the spindle or shaft extension 15 by a groove 21 therein and a spline or key 22 so that the shaft extension may rotate with the pulley and be longitudinally slideable therein. The pulley may have a collar 23 attached to one face and provided with an annular flange 24 adapted to co-operate with the walls of a recessed member 25 formed as part of a bracket 27 which sup-

ports the boxing 18 as illustrated in Figure 1, or with a flange 26 extending up from the base of bracket 27 as illustrated in Figure 10 of the drawings, so that under either form the pulley will rotate with the shaft 14 or its extension 15 and be prevented from moving longitudinally of the shaft or its extension. Encircling the shaft extension 15, within the tubular spindle 7, between the cap 16 and the shouldered end of spindle 14 are 5 two rings or collars 28, between which are balls 29, forming a thrust-ball-bearing which moves with the tubular spindle and its interior rotatable and longitudinally movable spindle which carries the boring-bit. The boring-bit is indicated by the numeral 30, and its shank 31 fits in a socket 32 formed in the end of the shaft or spindle 14, and is held by a set screw 33, accessible through opening 34 in boxing 6 and 35 in tubular spindle 14 and opening 36 in the metal (preferably bronze), bushing 37. The tubular spindle is held against rotation, say by keys 38 fitting in receiving recesses or grooves formed in the interior of boxing 6 and exterior of the tubular spindle 7, as clearly indicated in Figs. 5 and 6 of the drawings. The tubular spindle 7 and internal spindle 14 are moved into engagement with the work that will rest on 10 the work table 39, by means of a cable 40 connected at one end to the cap 16 of the tubular spindle 7 and passing through the hollow base of casting 4, and over a sheave 41 journaled in bearings 42 depending from 15 the underside of the base plate 2 at the upper end of standard 1, and will have its lower end connected to a suitable foot pedal (not shown) so that on depressing the pedal the spindle carrying the chisel and the spindle 20 carrying the boring-bit will be moved towards the piece of work on the work table. Around the cable 40 is a spiral compression spring 43 attached at one end to the casting 4 and at the other end to the tubular spindle 45 25 7, say through its end cap 16. This spring is placed under compression in the forward movement of the spindles carrying the chisel and boring bit, and when the cable 40 is released the recoil of spring 43 retracts the chisel and boring bit to normal position. A cushioning spring 44 is disposed in the path 30 of retraction of the chisel and boring bit spindles, say as illustrated in Fig. 1 of the drawings, so as to cushion the retraction of the parts.

A work table 39 is disposed in the path of travel of the chisel and boring bit to support the piece of work to be operated on. This table in the form illustrated in Figure 1, is provided with adjustable clamps 45 and 46 of a suitable type for holding the work on the table. The table is screw threaded to the upper end of a post 47 so as to be rotatively adjusted to present the work at the angle desired to the chisel and boring bit, and is

held to its adjustment by a set screw 48. The post 47 is preferably tubular and is vertically movable in a swinging hanger-sleeve 49 suspended from the forward end of the platform-plate 2 by a nutted bolt 50 which serves 70 as a pivot for the hanger. By loosening the nut on the bolt the hanger may be swung on its pivot so as to change the plane of the top of the table so as to present the work to the chisel and boring bit at the vertical 75 angle desired for the plane of the bore or cavity to be cut in the work, or in a true horizontal plane as desired, and when adjustment has been made to the plane desired, the nut on the bolt is tightened and the 80 hanger held to its adjustment. The post is slidable within the sleeve-hanger 49 and is prevented from rotating therein by keys 51 fitting in recesses formed in the sleeve 49 and post 47 as clearly shown in Fig. 3 of the 85 drawings. The post 47 is raised and lowered by a screw 52 threaded into a cross-bar 53 at the lower end of the post and provided with a collar 54 secured by a set screw 55 to the lower end of the screw, above a removable 90 plate 56 secured by bolts 57 to the end of the sleeve hanger as shown in Fig. 1 of the drawings, and also with a collar 58 secured by a set screw 59 to the end of screw 52 beneath the plate 56 and having a crank handle 60 95 for operating the screw.

Figure 7 illustrates a vertical disposition of the parts of the mortiser instead of a horizontal position as illustrated in Figure 1. The several elements constituting the machine are substantially the same as corresponding parts shown in Figure 1 and accordingly the same reference numerals in Figure 7 are used for corresponding elements found in Figure 1, and as the construction is 100 substantially the same a showing of the details of the various elements is unnecessary. In the form of Figure 7, the work table designated by the numeral 39a is illustrated as stationary as the chisel and boring bit 105 are moved downwardly toward the table and therefore it is not necessary to have the table move upwardly towards the chisel and boring bit. Also as illustrated in Figure 7 the base plate 2 may be bolted or otherwise attached 110 to the face of a suitable upright support 1a. 115

In Figure 8 is illustrated a disposition of the parts of the machine in an upright instead of in a horizontal plane, and in which a suitable form of electric motor 61 may be used 120 for rotating the spindle 14, 15 which carries the boring bit instead of a line shaft driven pulley shown in Figures 1 and 7. Either a line shaft driven pulley, or an electric motor may be used in any of the different forms 125 illustrated, and hence both types of driving means for the rotating spindle have been shown. In the form of machine shown in Figure 8 the base plate 2 is shown attached by bolts, or otherwise, to an upright sup- 130

port or standard 1a, and a work table 39b is shown as having a post 47b slideable in a sleeve 49b which may be attached by a bracket 50b and bolt 51b to the standard 1a. The post 47b may be raised and lowered by a screw lifting means like that illustrated for the form shown in Figure 1 of the drawings and therefore not needing a detailed illustration and description. The parts in Figure 8 corresponding to like parts in Figure 1 bear corresponding identifying numerals and in view of the previous description need no repetition of the description.

Figure 9 is similar to Figure 8 in the parts and their operation except in Figure 9 the cable 40 is omitted and a hand grip 62 used for moving forward the spindles which carry the chisel and boring bit. While a work table will be employed none is illustrated in Figure 9.

20 A mortiser built as illustrated and described costs very much less than other machines in manufacture and is efficient in operation and not liable to get out of good working condition. The preferred details 25 of the various forms have been illustrated and described with fullness but it is to be understood that changes may be made in some details and essential features sought to be defined by the claims still be retained.

30 The base plate which carries the tubular boxing and associated elements, instead of being supported from a standard or post, may be attached to a suitable table of any desired form and construction as a support for the parts, but as the table does not constitute the inventive features it is not illustrated in the drawings but will be understood clearly by those skilled in the art.

40 Having described my invention and set forth its merits what I claim is:—

1. A mortising machine comprising a bed or plate having two spaced projecting members each having a tubular bearing portion 45 parallel to said plate, a tubular splined sliding spindle guided in one of said bearing portions and carrying a hollow mortising chisel, a bit spindle sliding and rotating in the other of said bearing portions and also 50 in the tubular splined spindle, having a thrust bearing engagement with the splined sliding spindle and carrying a bit projecting into said hollow chisel, means for rotating said bit spindle having a sliding rotation 55 producing relation to said spindle, and means for rotatably connecting said means to the bearing portion in which the bit spindle rotates; an operating cable secured to the splined sliding spindle and running parallel thereto and between it and said bed plate 60 and through the member having the bearing portion in which the splined member slides, a spiral spring surrounding said cable partly enclosed in the said bearing portion member 65 and having its reaction bearing therein for

one end of the spring and the other end of the spring engaging the means for connecting the cable to the splined sliding spindle.

2. A mortising machine comprising a bed or plate having two spaced projecting members each having a tubular bearing portion parallel to said plate, a tubular splined sliding spindle guided in one of said bearing portions and carrying a hollow mortising chisel, a bit spindle sliding and rotating in the other of said bearing portions and also in the tubular splined spindle, having a thrust bearing engagement with the splined sliding spindle and carrying a bit projecting into said hollow chisel, means for rotating said bit spindle having a sliding rotation producing relation to said spindle, and means for rotatably connecting said means to the bearing portion in which the bit spindle rotates; an operating cable secured to the splined sliding spindle and running parallel thereto and between it and said bed plate and through the member having the bearing portion in which the splined member slides, a spiral spring surrounding said cable partly enclosed in the said bearing portion member and having its reaction bearing therein for one end of the spring and the other end of the spring engaging the means for connecting the cable to the splined sliding spindle; said machine 95 also including a swinging hanger arm pivotally supported from one end of the bed or plate which supports the chisel tubular splined spindle and the rotatable and slideable bit spindle, said hanger being formed 100 with a tubular sleeve to receive a work-table supporting the post, and means for securing the table and hanger in their respective adjustments.

In testimony whereof I affix my signature. 105
FREDERICK W. MONROE.
